SHOWER HEAD

Irving H. Russell, Oak Park, Ill., assignor to Sloan
Valve Company, Chicago, Ill., a corporation of
Illinois

Application November 5, 1948, Serial No. 58,498

8 Claims. (Cl. 299—59)

1

The present invention relates to shower heads of the type commonly used in shower baths, and the principal object of the invention is to provide a new and improved automatic self-cleaning shower head.

Another object of the invention is to provide a new and improved shower head which automatically flushes out any sediment or foreign deposits tending to clog the spray outlet grooves.

A further object is to produce an improved shower head which will instantly discharge all residual water remaining in the shower head after water flow ceases, so there is no subsequent dribble.

Another object of the invention is to produce a shower head in which the water dispersing disc is normally spaced away from the spray outlet and responsive to water flow through the device, is automatically moved into engagement with the spray outlet to produce a multiplicity of jet discharge orifices.

Still further objects are to provide a new and improved shower head which is simple but durable in construction; is highly efficient and reliable in performing its intended functions, which can be economically manufactured in high production machinery so the device can be sold at low cost; and finally which does not require constant maintenance and service over long periods of operation.

With the foregoing and other objects in view, the invention consists in certain novel features in construction, operation, and combination of the various elements as will be more fully described and pointed out hereinafter.

Referring to the drawings:

Fig. 1 is a sectional view through a shower head embodying the invention;

Fig. 2 is a similar sectional view showing the shower head in operation with water flowing through the device;

Fig. 3 is an end view of Fig. 1;

Fig. 4 is a side view of the internal assembly unit of the device;

Fig. 5 is a modified form of the invention;

Fig. 6 is another modification;

Fig. 7 shows a cross-section of a different form of the invention in which the piston is movable, while

Fig. 8 is a cross-section taken generally along the line 7—7 of Fig. 7.

In a large number of shower heads in general use at the present time there is a fixed water dispersing disc arranged across the outlet end of the shower head, which is provided with a multiplicity of small jet discharge passages over its surface. As is well known, this type of shower

2

head eventually becomes completely clogged up with lime deposits or sediment carried along in the water supply. This necessitates thorough cleaning of the jet orifices, and where a large number of shower heads are provided, as in public places, constant maintenance is required.

Other shower heads, of which a large number are in use at the present time, are provided with a manually operated handle which is connected to an adjustable water dispersing disc, so that the disc may be raised or lowered in the spray outlet to regulate the annular jet discharge. After use by a person, the handle must be turned to lower the water dispersing disc and permit a large flow

15 of water to pass out of the shower head, thereby flushing out and cleansing the same. In still other shower heads, the water dispersing disc is adapted to be axially screwed outward from the annular spray discharge opening to permit flushing out of sediment when necessary. In both of these prior devices, the eventual accumulation of lime deposits and sediment results in gradual unsatisfactory operation of the shower heads because it has been found from observation that the user of the shower head often neglects to fully open the water dispersing disc from the spray outlet, so that eventually the jet discharge grooves become clogged up.

30 A further objection to the foregoing types of shower heads is that after the water supply has been turned off by a user, there is always a long drawn out dribble of water from the shower head which is objectionable and annoying to the user.

The foregoing disadvantages have all been 35 overcome by the present invention, in which the shower head is automatically self-cleaning and permits instant discharge of the accumulated water in the shower head after the supply valves are turned off. Accordingly, the jet discharge orifices will not become clogged up and the spray discharge therefrom will always be constant and of the desired character.

Referring now particularly to Fig. 1, which discloses a preferred embodiment of the invention, the general outward appearance of the shower head is of conventional shape, the internal mechanism, however, being entirely different as will now be pointed out.

The shower head casing comprises a bell-shaped body 5 having a lower flanged portion 6 surrounding the spray outlet or discharge end 7. The upper neck portion 8 of the body 5 is arranged to be carried or supported from a coupling nut 9 threaded thereon which clamps a universal swivel joint or ball 10 directly against the packing ring 11, located in the top of the shower head casing to permit swinging the shower head in any

desired direction. A nipple 12 is formed integral with the ball 10 and may be threaded onto a pipe carrying the inlet water supply through the nipple passage 13. The passage 13 connects directly with the water passage 14 through the ball 10.

In order to regulate the water flow through the passage 14, and thereby the force or velocity of the spray emitted, a throttle valve is provided on the shower head. This comprises a manual rotatable knob 15, having a shaft extending through packing nut 16 in the side of the nipple 12. The valve opening 17 of the throttle 15, when turned in the direction shown in Fig. 1, shuts off the water supply, and in the position shown in Fig. 2, permits water to enter the passage 14. A small circular groove 18 surrounding the shaft of throttle 15 on both sides of the valve opening 17 permits a small leak in the supply line to prevent reverse flow between the hot and cold water supply valves connected to the nipple 12 in case the pressure of one exceeds the other.

The water passes through the shower head from passage 14 and extends through a hollow piston stem 21. This hollow stem at its upper end is threaded directly into a partition 22 formed across the upper end of the casing 5 and has a passage 23 extending axially therein with a series of transverse orifices 24 at the bottom end of the stem. The hollow stem 21 is provided with a screw driver slot 25 at its lower end to permit it to be screwed into the body 5 from the open end thereof into the partition 22, and a nut 26 also threaded onto the lower end of the hollow stem 21 clamps a stationary piston member 27 upon the stem. This stationary piston 27 is preferably formed of molded firm synthetic rubber having a reinforcement washer 28 imbedded therein to lend rigidity to the same.

Located within the open end of the shell casing 5 is a hydraulic cylinder 31, which is cup-shaped, having its open upper end internally threaded to receive a second inverted cup-shaped member 32. This cup member 32 has an opening 33 through which the stem 21 slidably extends and the cup forms a hydraulic pressure chamber 34 directly above the stationary piston 27. Below the stationary piston 27, the hydraulic cylinder 31 forms the relief chamber 35. Located within the relief chamber 35 and encircling nut 26 is a restoring spring 37 exerting its pressure between the bottom of the piston head 27 and the bottom of the hydraulic cylinder 31, so that cylinder 31 is normally urged in a downward direction by the spring 37, and the open end of the upper cup 32 contacts the top side of piston 27 and rests thereon.

At a point approximately midway of the length of hydraulic cylinder 31 is a series of orifices 36 extending through the walls of the cylinder. These orifices are preferably four in number and are of a size or total cross-sectional area less than the hollow stem orifices 24. It will be observed that an annular space 39 is formed between the outside walls of hydraulic cylinder 31 and the inside walls of the casing 5 for the passage of water therethrough.

Located normally in juxtaposition to the spray discharge opening 44 is an annular water dispersing disc 40, having a series of jet discharge passages or grooves 41 formed around its periphery and inclined at an angle outward with respect to the axis of the shower head. These grooves 41 cooperate with the smooth inner surface of the spray outlet 7 and are substantially parallel therewith to form the cone-shaped spray

pattern made up of individual streams corresponding to each groove 41. The water dispersing disc is preferably made of some synthetic plastic product, preferably "Bakelite," which has the property of resisting corrosion and preventing the accumulation of sediment from the water. The disc 40 is provided at its upper surface with a pair of lugs 42, adapted to register loosely with holes formed in the bottom of the hydraulic cylinder 31 to prevent relative rotation therebetween, as when the disc 40 is clamped directly onto the lower end of cylinder 31 by the knurled clamp screw 43, screwed axially in the bottom of the cylinder. It will be noted that the spray dispersing disc 40 is normally projected outward from the spray outlet 7 to provide a relatively large annular discharge opening 44.

The knurled screw 43 is provided with a bore 46 for the accommodation of a secondary water dispersing member 47, which is adapted to loosely rest on the bottom ledge of the bore 46 directly over a jet discharge orifice 48. A pair of flutes 49 are formed on opposite sides of the dispersing member 47 to provide passages for the water 25 through the jet discharge nozzle 48.

In assembling the shower head, the hollow stem 21 is first passed through the opening 33 of the upper cup member 32, after which the hydraulic cylinder 31 is threaded onto the upper cup 32, the spring 37 being first placed under the head of nut 26. This primary assembly is then placed inside of the casing 5 and a screw driver applied to the lower slotted end 25 of hollow stem 21 and the stem threaded into partition 22, the screw driver having access to the slot 25 through the axial opening in the bottom of cylinder 31. Next, the disc 40 is placed in position on the bottom of the cylinder 31, with the lugs 42 in registry with the holes in the bottom of the cylinder. The periphery of disc 40 is then grasped and the assembly held from rotation while the knurled screw 43 is screwed into the cylinder 31, thereby clamping the disc 40 in position. The complete assembly and its external appearance is depicted in Fig. 4, which shows knurled surfaces on cylinders 31 and 32 to facilitate their assembly.

Referring now to the operation of the shower head in connection with Fig. 2, it will be observed that the throttle valve 15 is turned to permit passage of the water from the inlet supply passage 13 to the passage 14. The opening or closure of this throttle valve, however, is not necessary each time the shower head is used, its principal purpose being to throttle the supply of water to the desired flow when the pressure is excessive, the usual thermostatic mixing valve or the separate hot and cold valves being used for shut-off purposes.

The inlet water flow from the passage 14 extends through the hollow interior passage 23 of stem 21 and out transversely through the series of orifices 24 into the pressure chamber 34. At the instant that the water flow takes place, as in Fig. 1, there will be no direct outlet for the water flow, but as the pressure builds up in the pressure chamber 34, which will be practically instantaneous, the pressure is exerted upward against the underside of the cup 32, forcing the same to rise upward along the outside of piston stem 21. This movement carries along the hydraulic cylinder 31 upward against the small amount of tension exerted by restoring spring 37 and in sliding engagement with stationary piston 27. This upward motion of the hydraulic unit continues until the periphery of the water dis-

persing disc 40 and its grooves 41 have been moved into closing or contacting engagement with the annular spray outlet opening 7 of the casing 5, thereby stopping the movement. An instant before this action takes place, the cylinder orifices 36 will have been moved into a position where they are approximately parallel with the upper surface of the stationary piston 27, as shown in Fig. 2. This permits the passage of water outward through the orifices 36 and into the annular chamber 39 between cylinder 31 and casing 5. Water flow continues outwardly through the annular disc grooves 41, resulting in the discharge of a cone-shaped spray formation from the spray outlet 44 and individual jet streams corresponding to each groove 41. It will be observed that the cylinder orifices 36 are of a smaller cross-sectional area than the orifices 24 in the stationary piston stem 21. This is to enable a certain amount of back pressure to be built up within the chamber 34 to provide a head of water sufficient to maintain the hydraulic cylinder 31 in its upward position and the water dispersing disc 40 in the jet discharge position, as long as water flow takes place through the shower head.

From the foregoing, it is apparent that the movement of the water dispersing disc 40 is in a direction in opposition to the flow of water through the shower head with the piston 27 remaining stationary while the hydraulic cylinder moves upwardly. It will also be observed that no water flow can take place and no spray formation emitted until the disc 40 is completely into engagement with the annular spray outlet 7 of the shower head, which can only occur when orifices 36 are moved into a position above piston 27. A perfect spray formation is therefore emitted at once and instantly instead of gradually as in all other shower heads.

Upon the cessation of water flow through the shower head, as when the shut-off valves are closed, the pressure within the pressure chamber 34 is reduced and the restoring spring 37 is effective to exert its pressure against the bottom side of hydraulic cylinder 31. This pressure, of course, is assisted by gravity as well as the weight of the remaining amount of water in the shower head. The hydraulic cylinder 31 slides downward along the stationary piston 27 until the upper surface of piston 27 is contacted by the bottom of upper cup member 32, stopping the movement. At the same time, the water dispersing disc 40 moves downward and outward away from engagement with the spray outlet 7, widely opening up the annular passage 44 to permit the instant discharge of the remaining amount of water in the head after the supply valves have shut off, whereby no annoying prolonged dribble of water will take place.

It will be observed that the foregoing action and the inward and outward movement of the spray dispersing disc 40 takes place each time the shower head is turned on and off. The action is entirely automatic and results in the immediate cleansing or flushing out of any sediment which may lodge within the grooves 41 or above the spray outlet 7 when the disc is closed upon it.

It has been found in practice that where the rubber stationary piston head 27 has sliding contact with the inner walls of the hydraulic cylinder 31, there will be a small amount of leakage due to the pressure built up within the pressure chamber 34. This leakage will pass into the lower chamber 35, and unless some provision was made for relieving the same, the operation

of the device would not be entirely reliable at all times. This relief has been accomplished by permitting the leakage in chamber 35 to pass out through the bore 46 of the clamping screw 43, through the water dispersing member 47 and out of the jet nozzle 48. The jet discharge from the nozzle 48 provides a secondary small discharge arranged axially within the cone-shaped spray discharge emitted from the annular spray outlet 44. This is a desirable feature since it provides an additional spray discharge to a user of the shower head which would not be available from the circular cone spray itself. The small dispersing member 47 being loosely positioned in the bore 46, and having relatively large discharge passages 49, is not subjected to clogging, since foreign material will readily pass out of the relatively large openings. It has been observed that if a transverse slot 50 is cut across the bottom of the dispersion member 47 connecting the two flutes 49, a better and more desirable spray pattern formation is provided for the jet nozzle 48.

Referring now particularly to Fig. 5, this is a further exemplification of the invention illustrating similar operating principles in a shower head, resulting in certain economies in construction. In this modification, the body 51 is preferably bell-shaped, having a flange 52 formed on its lower spray outlet end. A hollow stem 53 is threaded into an upper partition of the body 51 and has a headed portion 54 formed on its lower side and provided with a screw driver slot, so that the stem may be threaded into the body partition. An axial opening 55 extends through the stem 53 and provides a passage leading to the series of orifices 56 in the bottom of the stem 53. A hydraulic cylinder 57 of generally inverted cup-shaped structure is provided at its upper end with an opening through which the stem 53 extends, and with which the cup has sliding movement. At the side walls a series of spaced orifices 58 are provided in cup 57, which are smaller than orifices 56 and are located directly below a rubber packing member 59, forced onto the screw head 54. The hydraulic cylinder 57 is normally urged into its lower outward position by an expansion spring 60 pressing against washer 61 on top of the cylinder 57 and at its other end against the upper body partition 51. At its lower open end, the hydraulic cylinder 57 supports a water dispersing disc 62, which is attached to the same by a series of screws 63 threaded into the flanged rim 64 of the cup. In the normal position as shown, a large annular water discharge opening 65 exists between the water dispersing disc 62 and the shower head flange 52. A knurled nut 66 is preferably screwed in the bottom of the water dispersing disc.

In the operation of this modification, the water passes through the hollow stem 53 and the orifices 56 therein, and builds up pressure in the pressure chamber 67, causing the hydraulic cylinder 57 to move upwardly and the disc 62 to move into water dispersing engagement with the flange 52, causing an annular jet discharge from the shower head opening 65. In order to provide a relief in the cylinder 57, below the piston head 54, a small hole 68 may be provided to serve as an outlet for any water escaping around the end of the piston packing 59. In this construction of shower head, the action is similar to that described in connection with the preferred embodiment illustrated in Figs. 1 and 2, in that the initial water flow into the device does not result in the immediate formation of a jet discharge

from the spray outlet until the disc 62 is moved into place against the flange 52 of the casing, after which the pressure within the pressure chamber 67 holds it in that position. Upon the cessation of water flow, the disc 62 is immediately projected outward from the spray outlet, resulting in the immediate discharge of the accumulated water in the casing 51, so that no resultant dribble can take place.

Referring now to the second modification of the invention illustrated in Fig. 6, the general arrangement is somewhat similar to the previous disclosures in that the shower head casing 71 is provided with a spray outlet flange 72 and a hollow piston stem 73 threaded into the partition formed in the upper end of the casing 71. At its lower end, clamping nut 74 is threaded onto the stem 73 and an axial hollow portion 75 in stem 73 terminates in a series of transverse orifices 76 located near the lower end of the stem. An inverted cup-shaped member 77 forming the hydraulic movable cylinder, has an opening 78 at its upper end, which normally rests in the position shown upon an annular shoulder or flange 79 formed in the stem 73. Engaging in slidable relationship with the inner walls of the hydraulic cylinder 77 is a cup-shaped packing member 80 clamped in position on the lower end of stem 73 by the nut 74. A restoring spring 81 has one end in abutting relationship with the bottom of the cup member 80, and its other end bearing against a closure disc 82 threaded into the open end of hydraulic cylinder 77. The spring 81 normally exerts its pressure against the cylinder 77 to hold the upper edge and opening 78 against the shoulder 79. A water dispersing disc 83 is arranged in operative relation to the spray outlet 72, and is provided with a series of jet discharge openings 85 around its periphery. The nut 84 clamps the dispersing disc 83 directly onto the closure member 82, carried by cylinder 77.

As in the other modifications of the invention, water flow through the hollow stem 75 and orifices 76 creates a pressure above the piston member 80, resulting in upward movement of hydraulic cylinder 77 until its upper end is spaced away from the ledge 79, whereupon water flow will take place through the orifices 78 and annular passage 86 between the outside of cylinder 77 and the inside of casing 71. At this time, the disc 83 is in spray discharge engagement with the outlet opening 72 of the casing 71 and a cone-shaped spray discharge is ceased to be emitted through the grooves 85. Upon the water flow ceasing to take place, the spring 81 immediately projects the disc 83 outward, resulting in quick discharge of the remaining volume of water in the shower head.

A still further modification of the invention is illustrated in Figs. 7 and 8. In this arrangement, however, contrary to the previously described modification, the piston instead of being stationary, is movable, while the enclosing cylinder is stationary. This requires a somewhat different structural arrangement of the shower head, although the principles of operation are essentially the same.

The shower head casing 90 is of bell-shaped construction, and is provided with the lower flange portion 91 comprising the spray outlet. A piston having a headed portion 92 fits fairly closely and reciprocates within an inverted cup-shaped cylinder 93, while the stem portion 94 of the piston head 92 extends downward and at its

lower end carries the water dispersing disc 95 clamped in place on the stem 94 by the clamp screw 96. A closure member 97 threaded on the inner surface of casing 90 serves as a bearing for the stem 94 and has an upwardly projecting bearing portion 95', upon which the head of piston 92 normally rests. The closure member 97 is threaded inward until it engages the open end of the cylinder 93 to tightly hold it within casing 90. At its upper end, a protruding boss 98 is formed on the top side of cylinder 93 to register with water passageway 99 in the casing and prevent rotation of the cylinder within the casing. A restoring spring 100 arranged between the water dispersing disc 95 and the closure disc 97 normally holds the piston head 92 on the shoulder 95' of disc 92 and the disc 95 outward from the spray outlet 91. Water passages are formed in the body including passages 99, 101, 102 and 103, the passage 101 leading to two opposite sides of the cylinder 93, as indicated in Fig. 8, and into oppositely disposed orifices 104 extending through the wall of cylinder 93 to the underside of piston head 92. Another pair of oppositely disposed water passages 103 connect the orifices 105 in the cylinder 93 above piston 92 to the water dispersing disc 95 and the spray outlet. As viewed in Fig. 8, the pair of passages 102 and 103 being adjacently disposed, are separated by a series of projections 106 formed in the inner walls of casing 90.

Water flow through the device takes place through passages 101, 99 and 102, and orifices 104, causing pressure formation within the chamber 107 below piston head 92 to raise it upwardly until it is moved past the position directly opposite the upper cylinder orifices 105, wherupon the water pressure is relieved and passes through the orifices 105 and outwardly through the two passages 103 to the spray outlet. At this time, the disc 95 is in registry with the spray outlet 91 to cause a spray discharge. Upon water ceasing to flow through the device, the spring 100 forces the disc 95 outward assisted by gravity and causes the piston 92 to assume its lowermost position. In this modification, it will be seen that the flow of water through the shower head is in a direction opposite to that in which the disc 95 is moved each time, and upon water flow ceasing to take place, the disc is immediately projected outward into position to permit full discharge of the water.

The invention has been described herein more or less specific as to details, including several modified forms thereof, yet it is to be understood that the invention is not to be limited thereby, as changes may be made in the arrangement and proportion of the parts and elements, and that equivalents may be substituted therefor, without departing from the spirit and scope of the invention as set forth in the appended claims.

What is claimed is:

1. In a self-cleaning shower head, a casing having a water supply inlet and a spray outlet, a movable hydraulic cylinder inside said casing but separated from the side walls thereof, a water dispersing disc attached to one end of said cylinder and positioned in spaced relation to said spray outlet, a stationary piston within said cylinder having a hollow supporting stem attached to said casing, the water flow through said hollow stem and into said cylinder causing said cylinder to be moved within said casing and thereby move said disc into water dispersing position in said spray outlet, said cylinder having orifices in the

sides thereof normally blocked by said piston and opened only when said cylinder has positively moved said disc into said spray outlet whereby a water passage is provided extending from said hollow stem through said cylinder orifices to the side walls of said casing into said spray outlet.

2. In a self-cleaning shower head, a casing having a water supply inlet and a spray outlet, a movable hydraulic cylinder inside said casing but separated from the side walls thereof, a water dispersing disc positioned adjacent said spray outlet, and attached to one end of said cylinder, a stationary piston inside said cylinder having a hollow stem projecting from the other end of said cylinder, the end of said stem being attached to said casing whereby said cylinder and disc are supported by said piston, the flow of water through said casing and said hollow stem into said cylinder causing said cylinder to be raised from said piston to move said disc into water dispersing engagement with said spray outlet, said cylinder having orifices in the sides thereof normally blocked by said piston and opened only when said cylinder has positively moved said disc into said spray outlet whereby a water passage is provided extending from said hollow stem through said cylinder orifices to the side walls of said casing into said spray outlet.

3. In a self-cleaning shower head, a casing having a water supply inlet and a spray outlet, a movable hydraulic cylinder inside said casing but separated from the side walls thereof, a water dispersing disc positioned across but outward from said spray outlet and fastened to one end of said cylinder, a stationary piston in said cylinder having a hollow stem projecting from the other end of said cylinder, the end of said hollow stem being attached to said casing leading to said water supply inlet, said hollow stem being provided with water flow orifices leading into said cylinder on one side of said piston, said cylinder being provided with water flow orifices leading from the other side of said piston into said casing side walls and said spray outlet, the water flow through said casing and said hollow stem orifices causing said cylinder to be raised to a position where said cylinder orifices and said stem orifices coincide to permit water flow therethrough, the movement of said cylinder also causing said disc to be moved into engagement with said spray outlet to cause a dispersing spray to be emitted from said spray outlet.

4. In a self-cleaning shower head, a casing having a water supply inlet and a spray outlet, a movable hydraulic cylinder in said casing but separated from the side walls thereof, a water dispersing disc attached to said cylinder and normally arranged across but out of engagement with said spray outlet, a piston in said cylinder having a projecting hollow stem attached to said casing, water flow through said casing and into said hollow stem and cylinder causing said cylinder to be moved with respect to said piston whereby said disc is moved into water dispersing engagement with said spray outlet, said cylinder having orifices in the sides thereof to provide a water passage extending from said hollow stem through said cylinder orifices to the side walls of said casing and into said spray outlet and cooperative means on said piston and said cylinder for preventing water flow through said water passage and spray outlet until said disc is moved into engagement with said spray outlet.

5. In a self-cleaning shower head, a casing having a water supply inlet and having a spray

outlet, a water dispersing disk and a guiding connection between the disk and the casing formed and adapted to guide the disk toward and away from the spray outlet, said disk having an edge portion conforming substantially to the inner diameter of the spray outlet when opposed thereto, an assembly for moving the water dispersing disk against said spray outlet in response to a flow of water inwardly through the water supply inlet, said assembly including means adapted to initiate the flow of water between the disk and the spray outlet at the end of the movement of the disk toward the spray outlet, the opposed edge surfaces of the spray outlet and the disk being shaped to define circumferentially spaced jet discharge orifices, and means for moving the disk to a position withdrawn from said spray outlet, when the flow of water through the water supply inlet is terminated.

6. The structure of claim 5 characterized in that the assembly includes an apertured shutter element and an opposed closure element cooperating therewith, one such element being fixed in relation to the casing and the other such element being mounted for movement in unison with the disk.

7. In a self-cleaning shower head, a casing having a water supply inlet and having a spray outlet, said outlet having a circumferential lip fixed in relation to the casing, a water dispersing disc and a guiding connection between the disc and the casing formed and adapted to guide the disc toward and away from the lip, said disc having an edge portion conforming substantially to the inner diameter of the lip when opposed thereto, an assembly for moving the water dispersing disc against the lip in response to a flow of water inwardly through the water supply inlet, said assembly including means adapted to initiate the flow of water between the disc and the lip at the end of the movement of the disc toward the lip, the opposed edge surfaces of the lip and the disc being shaped to define circumferentially spaced jet discharge orifices, and means for moving the disk to a position outwardly withdrawn from the lip when the flow of water through the water supply inlet is terminated.

8. The structure of claim 7 characterized in that the assembly includes a hollow guiding stem fixed on the casing and a piston member fixed on the stem, and a cylinder to which the disc is secured, movable on the stem and with respect to said piston, the cylinder including a ported wall portion opposed to said piston member and movable with the cylinder to place the water inlet in communication with the jet discharge orifices.
